UNITED STATES PATENT OFFICE.

CARL T. OSTERBERG, OF MILWAUKEE, WISCONSIN, ASSIGNOR OF ONE-HALF TO ALLEN HUDSON, OF MILWAUKEE, WISCONSIN.

CALCULATING DEVICE.

1,310,961.

Specification of Letters Patent. Patented July 22, 1919.

Application filed September 20, 1918. Serial No. 254,935.

To all whom it may concern:

Be it known that I, CARL T. OSTERBERG, a citizen of the United States, and resident of Milwaukee, in the county of Milwaukee and 5 State of Wisconsin, have invented new and useful Improvements in Calculating Devices, of which the following is a description, reference being had to the accompanying drawings, which are a part of this specification.

10 This invention relates to improvements in calculating devices.

It is one of the objects of the present invention to provide a calculating device of very compact size which may be easily carried in the pocket or in a hand bag and is 15 adapted to easily indicate the amount of change to be received in purchasing articles.

A further object of the invention is to provide a calculating device which is so simple in construction and inexpensive to manufacture as to be particularly adapted for 20 advertising purposes.

A further object of the invention is to provide a calculating device which is of simple 25 construction, is strong and durable and is well adapted for the purpose described.

With the above and other objects in view, the invention consists of the improved calculating device and the parts and combinations 30 as set forth in the claims, and all equivalents thereof.

In the accompanying drawing in which the same reference characters indicate the same parts in all of the views:

35 Figure 1 is a front side view of the improved calculating device;

Fig. 2 is a view of the opposite or rear side thereof;

Fig. 3 is a view similar to Fig. 1 with the 40 front side portion removed;

Fig. 4 is a view similar to Fig. 2 with its rear side portion removed; and

Fig. 5 is a longitudinal sectional view on a larger scale, taken on line 5—5 of Fig. 1.

45 Referring to the drawing, the numeral 8 indicates the improved calculating device which comprises a front plate or sheet of material 9, a rear plate or sheet of material 10 in spaced relation thereto, and interposed 10 overlapped calculating disks 11 and 12. The plates and disks are preferably formed of celluloid and are connected together by tubular rivets 13 which serve as journals for 50 the disks 11 and 12.

The peripheral portions of the disks are 55 serrated or toothed as indicated by the numeral 14 and said peripheral portions project beyond the opposite ends of the plates to permit said disks to be easily turned by the fingers.

60 The disk 11 on its front side, shown in Fig. 3, has the numerals one to nine and naught delineated thereon in consecutive order clockwise and spaced circumferentially therearound as indicated by the numeral 15. The numerals are spaced a short distance from the periphery of the disk and between said periphery and said numerals and in radial alinement therewith the disk is provided with apertures 16.

65 An elongated opening aperture 17 formed in the plate 9 medially of and in alinement with the tubular pivots 13 is positioned to permit any one of the numerals and the alined aperture to be turned into register 70 therewith and be visible therethrough.

75 The disks overlap each other between the tubular rivets and the front face of the disk 12 which is positioned against the rear face of the disk 11 is also provided with a circumferential line of spaced numerals one to 80 nine and naught extending anti-clockwise as indicated by 18 which may be turned to register with one of the apertures 16 when said aperture is in register with the plate opening 85 17 and be visible through said openings.

The disk 12 is also provided with a circumferential line of apertures 19 which are in radial alinement with the numerals 18 except the naught, and is also provided with a 90 single aperture 20 which is in radial alinement with the naught of the line 18 but is closer to the periphery of the disk 12 than the line of numerals 18.

95 The rear or opposite side of the disk 11 has delineated thereon two circumferential lines of numerals 21 and 22 which register respectively with the aperture 19 and the aperture 20 of the disk 12 and also with an elongated opening or aperture 23 formed in 100 the rear plate 10. This last mentioned aperture is also located medially between the tubular rivets and in alinement therewith. The inner circumferential line of numerals 22 are arranged in successive 105 clockwise order from one to ten while the outer circumferential line of numerals 21 extend in successive clockwise order from

one to nine and naught, and while the numerals are in radial alinement with the inner line of numerals, said inner numerals are advanced one number in value over the 5 adjacent outer line numerals 21.

The rear side of the disk 12 is provided with a circumferential line of numerals 24 extending in spaced successive anticlockwise order from one to nine with one blank 10 space 25 and also having the character naught as indicated by 26 offset from said space and in circumferential alinement with the apertures 19 and in radial alinement with the aperture 20 to provide for carrying over 15 the figures into the tens column. In use the numerals on the front sides of said disks will register the amount of change to be received from one or more dollars. For example, if fifty-seven cents be spent the 20 disks are turned to indicate this amount on the rear or reverse side of the device as indicated in Fig. 2. When thus turned the numerals 43 of the opposite or front sides of the disks will be visible through the 25 opening of the front plate to indicate the amount of change to be received from one dollar. If, for instance, the purchase should amount to two dollars and fifty-seven cents and a tender of five dollars be made 30 it would only be necessary to mentally subtract the next highest dollar amount of the purchase which would be three dollars, from the five, leaving two dollars, and adding the two dollars to the forty-three cents to indicate 35 the correct amount of change to be received.

While for convenience of description the calculating device has been described as having a front side and a rear side, it is to be 40 understood that the sides are only relative in terms, and that the figures of either side can be used to indicate the amount spent, and the figures of the opposite side will indicate the amount remaining.

45 From the foregoing description it will be seen that the calculating device is of very simple construction, and is well adapted for the purpose described.

What I claim as my invention is:

50 1. A calculating device, comprising a pair of spaced plates having sight openings therein, and a pair of overlapped disks journaled between said plates and having circumferential lines of numerals on their 55 opposite sides which may be turned to register with the sight openings, said disks also having circumferential lines of apertures through which some of the numerals of one disk may be viewed through the apertures of the other disk.

2. A calculating device, comprising a pair of spaced plates having sight openings therein, and a pair of overlapped disks journaled between said plates and having

circumferential lines of numerals on their 65 opposite sides which may be turned to register with the sight openings, said disks also having circumferential lines of apertures which will register with the plate openings and through which some of the numerals of 70 one disk may be viewed through the apertures of the other disk.

3. A calculating device, comprising a pair of plates having sight openings therein, and a pair of disks journaled between 75 said plates and having overlapped portions between the plate openings, said disks having circumferential lines of numerals on their opposite sides and also having circumferential lines of apertures, said lines 80 of numerals and apertures being arranged to be moved to register with the sight openings of the plates and the disk apertures of one disk to register with some of the numerals of the other disk. 85

4. A calculating device, comprising a pair of plates having sight openings therein, and a pair of disks journaled between said plates and having overlapped portions between the plate openings, said disks having circumferential lines of numerals on their opposite sides and also having circumferential lines of apertures, one of said disks having a plurality of circumferential lines 90 of numerals on one of its sides, said lines of numerals and apertures being arranged to be moved to register with the sight openings of the plates and the disk apertures of one disk to register with some of the numerals of the other disk. 95

5. A calculating device, comprising a pair of plates having sight openings therein, and a pair of disks journaled between said plates and having overlapped portions between the plate openings, said disks having circumferential lines of numerals on their opposite sides and also having circumferential lines of apertures, one of said disks having a plurality of circumferential lines of numerals on one of its sides, the numbers of one line 100 of said plurality of circumferential lines of numerals being advanced one number in value over the adjacent line of numerals, said lines of numerals and apertures being arranged to be moved to register with the sight openings of the plates and the disk apertures of one disk to register with some of the numerals of the other disk. 105

6. A calculating device, comprising a pair of plates having medially positioned sight 110 openings, and a pair of disks journaled between said plates and having overlapped portions between the plate openings, each disk having circumferential lines of numerals on its opposite sides and one of the disks having a plurality of circumferential lines of numerals on one of its sides, each disk also having a circumferential line of 115 120 125

apertures arranged to register with numerals of the other disk, said numerals arranged in consecutive order.

7. A calculating device, comprising a pair 5 of plates having medially positioned eight openings, and a pair of disks journaled between said plates and having overlapped portions between the plate openings, each disk having circumferential lines of numerals on its opposite sides and one of the 10 disks having a plurality of circumferential lines of numerals on one of its sides, each disk also having a circumferential line of apertures arranged to register with numerals 15 of the other disk, said numerals arranged in consecutive order, the numerals of one disk extending in anticlockwise direction.
8. A calculating device, comprising a pair 20 of plates having medially positioned eight openings, and a pair of disks journaled between said plates and having overlapped portions between the plate openings, each disk having circumferential lines of numerals 25 on its opposite sides and one of the disks having a plurality of circumferential lines of numerals on one of its sides, each disk also having a circumferential line of apertures arranged to register with numerals 30 of the other disk, one of the disks having an aperture which is offset from the circumferential lines of apertures, said numerals arranged in consecutive order.
9. A calculating device, comprising a pair
- of plates having medially positioned eight openings, and a pair of disks journaled between said plates and having overlapped portions between the plate openings, each disk having circumferential lines of numerals on its opposite sides and one of the 35 disks having a plurality of circumferential lines of numerals on one of its sides, each disk also having a circumferential line of apertures arranged to register with numerals of the other disk, one of the disks 40 having an aperture which is offset from the circumferential lines of apertures and also having a numeral which is offset from one of the circumferential lines of numerals, said numerals arranged in consecutive order. 45
10. A calculating device, comprising a pair of plates having medially positioned eight openings, and a pair of disks journaled between said plates and having overlapped portions between the plate openings, said 50 disks having serrated peripheries which project beyond the opposite ends of the plates, each disk having circumferential lines of numerals on its opposite sides and one of the disks having a plurality of circumferential lines of numerals on one of its sides, each disk also having a circumferential line of apertures arranged to register with numerals of the other disks, said numerals arranged in consecutive order. 55

In testimony whereof, I affix my signature.

CARL T. OSTERBERG.
